16-FLUORO - 3 - KETO - 17 β -(β -HYDROXY - PROPA-NOYL) - Δ^4 - ANDROSTENES AND DERIVATIVES, THEREOF

Eugene J. Agnello and Gerald D. Laubach, Jackson Heights, N.Y., assignors to Chas. Pfizer & Co., Inc., Brooklyn, N.Y., a corporation of Delaware

No Drawing. Application March 23, 1959
Serial No. 800,997

2 Claims. (Cl. 167—77)

This application is concerned with new and useful steroid compounds and with compositions containing them. More particularly it is concerned with certain steroid compounds unsaturated at the 4-position; the 1- and the 4-positions; the 4- and the 6-positions or the 1-, 4- and the 6-positions, substituted at the 17-position with an α -hydroxy or β -hydroxy propanoyl group and having a 16 α -fluoro substituent. It is also concerned with therapeutically useful compositions containing these compounds together with pharmaceutically acceptable excipients.

The compounds within the purview of this invention include those having the formulas

and the Δ^1 -, the Δ^6 - and the $\Delta^{1,6}$ -dehydro analogs of these compounds wherein Y is selected from the group consisting of keto and β -hydroxyl and X is selected from the group consisting of hydrogen, halogen atoms, that is, fluorine, chlorine, bromine and iodine and methoxy and ethoxy groups.

Starting compounds which are used in the preparation of the valuable compounds of this invention include those having the formulas

wherein X and Y have the same meaning as above and Z is bromine or iodine. The Δ^1 -, the Δ^6 - and the $\Delta^{1,6}$ -dehydro analogs of these compounds are also used as starting materials in this invention.

2

The starting compounds are prepared in accordance with copending and concurrently filed patent application Ser. No. 800,996 which describes their preparation from the corresponding epoxide by treatment with hydrogen iodide or hydrogen bromide and subsequent separation of the isomers by chromatography.

For the preparation of the valuable compounds of this invention, the steroid compound with the side chain bromohydrin or iodohydrin function is treated with a de-brominating or deiodinating agent such as zinc and acetic acid or Raney nickel. It is preferred to use Raney nickel because of the ease of manipulation and the high yields which can be obtained.

Suitable solvents for carrying out the reaction with Raney nickel include reaction inert organic solvents such as lower aliphatic oxygenated solvents including ethers, alcohols, acids and ketones containing up to five carbon atoms. Methanol, ethanol, propanol, isopropanol, pentanol, acetone, methyl isopropyl ketone, dioxane, acetic acid and propionic acid are examples of suitable solvents. The use of a mixed solvent such as methanol-acetic acid is sometimes advantageous.

The amount of Raney nickel used is not critical although to insure the most economical utilization of the steroid starting material, it is generally preferred to use an excess of this dehalogenating agent. From four to twenty grams of Raney nickel per gram of steroid starting material has been found to provide suitable yields. The preferred excess, as will be recognized by those skilled in the art, will depend upon the degree of activity of the Raney nickel. This in turn will depend upon its previous treatment. With Raney nickel which has been washed first with water, then with acetic acid, then with methanol and finally with acetone in accordance with known procedures, it is usually found that from ten to fifteen grams of Raney nickel per gram of steroid leads to excellent yields. However, the Raney nickel can be used without previous treatment or with other known treatments and still function as a dehalogenating agent for the bromohydrin or iodohydrin.

The duration of the reaction is not critical depending only upon the degree of activity of the Raney nickel. This degree of activity is readily determined by tests well known to those skilled in the art, and include, for example, the reduction of known compounds requiring varying degrees of reducing activity. Reaction periods as short as five minutes and as long as twenty-four hours have been used. It is, however, generally found that excellent yields can be obtained using a reaction period of from five minutes to two hours.

For optimum yields the temperature of the reaction should be controlled so that it does not rise above 30° C. during the reaction period and it is best to carry out the reaction between 0° C. and 15° C.

Although it is not essential, it is preferred to carry out the reaction in an inert atmosphere such as a nitrogen atmosphere. This assures the most efficient use of the Raney nickel by minimizing its reaction with atmospheric oxygen.

The desired product can be isolated after removal of the Raney nickel by simply evaporating the solvent and purified by recrystallization from a suitable solvent such as ethyl acetate. It can also be purified by trituration with a suitable wash liquid such as ethyl acetate or ether-ethyl acetate.

If the solvent used is a lower aliphatic acid or a mixture containing such an acid it may be desirable to neutralize

the acid with an alkaline reagent such as ammonium or sodium hydroxide and to isolate the active compound by extraction from the neutralized aqueous mixture with an organic solvent. Suitable extraction solvents include water immiscible lower halogenated alkanes such as ethylene chloride, chloroform and carbon tetrachloride, or ketones such as methyl isobutylketones. The product is isolated from the extraction solvent and purified as described above.

The biologically active compounds of this invention which, as will be noted, may exist in epimeric forms may be administered alone or in combination with acceptable pharmaceutical carriers, the choice of which is determined by the preferred route of administration, the solubility of the compound and standard pharmaceutical practice. In general, the dosage of these compounds is of approximately the same order of magnitude as the dosage of hydrocortisone, and these compounds are useful to treat the types of pathological conditions often treated with hydrocortisone. Because of their great adrenocortical activity it is sometimes possible to use dosages of these compounds which are lower than those of hydrocortisone.

For oral administration the compounds may be administered in the form of tablets containing excipients such as starch or milk sugar. Aqueous suspensions and elixirs which may be sweetened or flavored may also be used. To apply these therapeutic agents topically, they may be prepared in the form of ointments and salves in suitable bases especially non-aqueous petrolatum type bases. For intra-articular injection aqueous suspensions may be employed. In this case various suspending and wetting agents may be added to the compositions to obtain a suspension not tending to settle out easily or to pack down in the bottle in which it is stored. Intramuscular and subcutaneous dosage forms may also be prepared by standard pharmaceutical practice.

The following examples are given solely for the purpose of illustration and are not to be construed as limitations of this invention, many apparent variations of which are possible without departing from the spirit or scope thereof.

EXAMPLE I

16α-fluoro-17β-(α-hydroxy-propanoyl)-Δ⁴ - androstadiene-11β,17α-diol-3-one

A solution containing 500 mg. of 16α-fluoro-17β-(α-hydroxy-β-bromo-propanoyl) - Δ⁴ - androstadiene - 11β, 17α-diol-3-one in 200 ml. of absolute methanol was cooled to 0° C. and 5 g. of Raney nickel in 50 ml. of methanol was added. The mixture was stirred for two hours, filtered and the methanol removed by evaporation. The residue was triturated with a 1:1 mixture of ethyl acetate and ether. The product was recovered by filtration.

EXAMPLE II

16α-fluoro-17β-(β-hydroxy-propanoyl)-Δ⁴-androstene-11β,17α-diol-3-one

A solution containing 500 mg. of 16α-fluoro-17β-(β-hydroxy-β-iodo-propanoyl)-Δ⁴-androstene-11β,17α-diol-3-one in 100 ml. of isopropanol was cooled to 10° C. and a mixture containing 4 g. of Raney nickel in 50 ml. of isopropanol was added. (The Raney nickel had been previously washed with water and then with diluted acetic acid to a pH of 7. It was then washed with methanol, the methanol removed and the Raney nickel refluxed for 30 minutes in acetone.) The reaction mixture was stirred for 15 minutes, filtered and the solvent removed in vacuo. The desired product was triturated with 1:1 ethyl acetate and ether and recovered by filtration.

The following compounds are prepared using the procedures of Examples I and II or the corresponding α-hydroxy-β-iodo; α-iodo-β-hydroxy; α-hydroxy-β-bromo and α-bromo-β-hydroxy-propanoyl compounds,

- 9α,16α-difluoro-17β-(α-hydroxy-propanoyl) - Δ⁴ - androstene-11β,17α-diol-3-one
 9α-chloro-16α-fluoro-17β-(α-hydroxy-propanoyl) - Δ⁴ - androstene-11β,17α-diol-3-one
 5 9α-bromo-16α-fluoro-17β-(α-hydroxy-propanoyl) - Δ⁴ - androstene-11β,17α-diol-3-one
 9α-iodo-16α-fluoro-17β-(α-hydroxy-propanoyl)-Δ⁴ - androstene-11β,17α-diol-3-one
 9α-methoxy-16α-fluoro-17β-(α-hydroxy-propanoyl) - Δ⁴ - androstene-11β,17α-diol-3-one
 9α-ethoxy-16α-fluoro-17β-(α-hydroxy-propanoyl)-Δ⁴ - androstene-11β,17α-diol-3-one
 16α-fluoro-17β-(α-hydroxy-propanoyl) - Δ⁴ - androstene-17α-ol-3,11-dione
 15 9α,16α-difluoro-17β-(α-hydroxy-propanoyl) - Δ⁴ - androstene-17α-ol-3,11-dione
 9α-chloro-16α-fluoro-17β-(α-hydroxy-propanoyl) - Δ⁴ - androstene-17α-ol-3,11-dione
 9α-bromo-16α-fluoro-17β-(α-hydroxy-propanoyl)-Δ⁴ - androstene-17α-ol-3,11-dione
 20 9α-iodo-16α-fluoro-17β-(α-hydroxy-propanoyl) - Δ⁴ - androstene-17α-ol-3,11-dione
 9α-methoxy-16α-fluoro-17β-(α-hydroxy-propanoyl) - Δ⁴ - androstene-17α-ol-3,11-dione
 25 9α-ethoxy-16α-fluoro-17β-(α-hydroxy-propanoyl)-Δ⁴ - androstene-17α-ol-3,11-dione
 16α-fluoro-17β-(β-hydroxy-propanoyl) - Δ⁴ - androstene-17α-ol-3,11-dione
 9α,16α-difluoro-17β-(β-hydroxy-propanoyl) - Δ⁴ - androstene-17α-ol-3,11-dione
 9α-chloro-16α-fluoro-17β-(β-hydroxy-propanoyl)-Δ⁴ - androstene-17α-ol-3,11-dione
 9α-bromo-16α-fluoro-17β-(β-hydroxy-propanoyl)-Δ⁴ - androstene-17α-ol-3,11-dione
 30 35 9α-iodo-16α-fluoro-17β-(β-hydroxy-propanoyl) - Δ⁴ - androstene-17α-ol-3,11-dione
 9α-methoxy-16α-fluoro-17β-(β-hydroxy-propanoyl) - Δ⁴ - androstene-17α-ol-3,11-dione
 9α-ethoxy-16α-fluoro-17β-(β-hydroxy-propanoyl)-Δ⁴ - androstene-17α-ol-3,11-dione
 16α-fluoro-17β-(β-hydroxy-propanoyl) - Δ⁴ - androstene-11β,17α-diol-3-one
 9α,16α-difluoro-17β-(β-hydroxy-propanoyl) - Δ⁴ - androstene-11β,17α-diol-3-one
 40 45 9α-chloro-16α-fluoro-17β-(β-hydroxy-propanoyl)-Δ⁴ - androstene-11β,17α-diol-3-one
 9α-bromo-16α-fluoro-17β-(β-hydroxy-propanoyl)-Δ⁴ - androstene-11β,17α-diol-3-one
 9α-iodo-16α-fluoro-17β-(β-hydroxy-propanoyl) - Δ⁴ - androstene-11β,17α-diol-3-one
 9α-methoxy-16α-fluoro-17β-(β-hydroxy-propanoyl) - Δ⁴ - androstene-11β,17α-diol-3-one
 9α-ethoxy-16α-fluoro-17β-(β-hydroxy-propanoyl)-Δ⁴ - androstene-11β,17α-diol-3-one
 16α-fluoro-17β-(β-hydroxy-propanoyl) - Δ⁴ - androstene-11β,17α-diol-3-one
 50 55 9α,16α-difluoro-17β-(β-hydroxy-propanoyl) - Δ⁴ - androstene-11β,17α-diol-3-one
 9α-chloro-16α-fluoro-17β-(β-hydroxy-propanoyl)-Δ⁴ - androstene-11β,17α-diol-3-one
 9α-bromo-16α-fluoro-17β-(β-hydroxy-propanoyl)-Δ⁴ - androstene-11β,17α-diol-3-one
 9α-iodo-16α-fluoro-17β-(β-hydroxy-propanoyl) - Δ⁴ - androstene-11β,17α-diol-3-one
 9α-methoxy-16α-fluoro-17β-(β-hydroxy-propanoyl) - Δ⁴ - androstene-11β,17α-diol-3-one
 9α-ethoxy-16α-fluoro-17β-(β-hydroxy-propanoyl)-Δ⁴ - androstene-11β,17α-diol-3-one
 16α-fluoro-17β-(β-hydroxy-propanoyl) - Δ⁴ - androstene-11β,17α-diol-3-one
 60 65 9α,16α-difluoro-17β-(β-hydroxy-propanoyl) - Δ⁴ - androstene-11β,17α-diol-3-one
 9α-chloro-16α-fluoro-17β-(β-hydroxy-propanoyl)-Δ⁴ - androstene-11β,17α-diol-3-one
 9α-bromo-16α-fluoro-17β-(β-hydroxy-propanoyl)-Δ⁴ - androstene-11β,17α-diol-3-one
 9α-iodo-16α-fluoro-17β-(β-hydroxy-propanoyl) - Δ⁴ - androstene-11β,17α-diol-3-one
 9α-methoxy-16α-fluoro-17β-(β-hydroxy-propanoyl) - Δ⁴ - androstene-11β,17α-diol-3-one
 9α-ethoxy-16α-fluoro-17β-(β-hydroxy-propanoyl)-Δ⁴ - androstene-11β,17α-diol-3-one
 16α-fluoro-17β-(β-hydroxy-propanoyl) - Δ⁴ - androstene-11β,17α-diol-3-one
 70 75 9α,16α-difluoro-17β-(β-hydroxy-propanoyl) - Δ⁴ - androstene-11β,17α-diol-3-one
 9α-chloro-16α-fluoro-17β-(β-hydroxy-propanoyl)-Δ⁴ - androstene-11β,17α-diol-3-one
 9α-bromo-16α-fluoro-17β-(β-hydroxy-propanoyl)-Δ⁴ - androstene-11β,17α-diol-3-one
 9α-iodo-16α-fluoro-17β-(β-hydroxy-propanoyl) - Δ⁴ - androstene-11β,17α-diol-3-one
 9α-methoxy-16α-fluoro-17β-(β-hydroxy-propanoyl) - Δ⁴ - androstene-11β,17α-diol-3-one
 9α-ethoxy-16α-fluoro-17β-(β-hydroxy-propanoyl)-Δ⁴ - androstene-11β,17α-diol-3-one
 16α-fluoro-17β-(β-hydroxy-propanoyl) - Δ⁴ - androstene-17α-ol-3,11-dione
 9α,16α-difluoro-17β-(β-hydroxy-propanoyl) - Δ⁴ - androstene-17α-ol-3,11-dione
 9α-chloro-16α-fluoro-17β-(β-hydroxy-propanoyl)-Δ⁴ - androstene-17α-ol-3,11-dione

What is claimed is:

1. A compound selected from the group consisting of those having the formulas:

and the Δ^{1} -, Δ^{6} - and $\Delta^{1,6}$ -dehydro analogs thereof wherein X is selected from the group consisting of hydrogen, halogen, methoxy and ethoxy; Y is selected from the group consisting of keto and β -hydroxyl.

- 5 2. A pharmaceutical composition comprising a compound as claimed in claim 1 together with a pharmaceutically acceptable carrier.
